CLAIM

(**) Term: **14 Years**

The ornamental design for keyboard with roller and volume dial, as shown and described.

(21) Appl. No.: **29/136,590**

DESCRIPTION

(22) Filed: **Feb. 1, 2001**

FIG. 1 is a perspective view of a keyboard with roller and volume dial showing our new design;
FIG. 2 is a top plan view thereof;
FIG. 3 is a rear elevational view thereof;
FIG. 4 is a left side elevational view thereof;
FIG. 5 is a right side elevational view thereof;
FIG. 6 is a front elevational view thereof; and,
FIG. 7 is a bottom plan view thereof.

(51) LOC (7) Cl. **14-02**

The broken lines are shown in the views for illustrative purposes only and form no part of the claimed design.
